UNITED STATES PATENT OFFICE.

WALKER J. BOUDWIN, OF SALT LAKE CITY, UTAH, ASSIGNOR OF ONE-HALF TO THE GENERAL ENGINEERING COMPANY, OF SALT LAKE CITY, UTAH, A CORPORATION OF UTAH.

CLASSIFIER AND DEWATERER.

1,197,255.

Specification of Letters Patent.

Patented Sept. 5, 1916.

Application filed May 10, 1915, Serial No. 27,075. Renewed July 25, 1916. Serial No. 111,278.

To all whom it may concern:

Be it known that I, WALKER J. BOUDWIN, a citizen of the United States, residing at Salt Lake City, in the county of Salt Lake 5 and State of Utah, have invented certain new and useful Improvements in Classifiers and Dewaterers, of which the following is a specification.

My invention relates to an apparatus for 10 classifying, washing, mixing and dewatering sands and slimes of ore wherein the ore is fed up an inclined surface and out of water onto an appropriate draining surface; and my invention consists of the parts and 15 the constructions, arrangements and combinations of parts which I will hereinafter describe and claim.

In the accompanying drawings forming 20 part of this specification and in which similar reference characters indicate like parts in the several views; Figure 1 is a top plan view of an apparatus constructed according to my invention. Fig. 2 is a vertical cross 25 sectional view of the same. Fig. 3 is a cross sectional view of an apparatus of modified form. Fig. 4 is a cross sectional view of another modification showing the use of my invention, as a drier and defrother on flotation concentrates, and the like. Fig. 5 is a 30 detail illustrating a modified arrangement of flights. Fig. 6 is a further modification.

A leading object of my invention is to 35 provide a simple and effective apparatus for classifying, washing, mixing and dewatering sands and slimes of ore. To this end, I mount upon a suitable foundation or framework, a pan-like structure of suitable diameter and which comprises an inverted cone, or funnel-shaped pan, A, the outer edge or 40 periphery of which is fashioned with an annular trough or launder, A', into which the sands and slimes are delivered, by appropriate conveying means such as flights, or rabbles, as I will hereinafter describe, said annular trough or launder having suitable discharge 45 openings for the delivery of the slimes and sands and to which openings the sands and slimes are conducted by appropriate flights, or other conveying means, hereinafter described.

At the apical or central portion of the 50 pan, there is provided a vertically extending tube, B, the top of which serves as an overflow edge for the water and fine slimes carried thereby, said tube serving, also, as a

means for maintaining the water level of the pan substantially constant, and the level being such that the upper portion of the pan is unsubmerged. The central tube, B, connects with a funnel-shaped lower portion, 60 B', having an outlet through which the overflow may be conducted to any suitable point.

Appropriately mounted vertically in line with the central or apical portion of the 65 cone, is a shaft, C, which is designed to be driven by some suitable mechanism, as the worm and worm wheel, K, K', shown, the lower end of said shaft being appropriately connected to a yoke or frame, D, whose side 70 members are connected to suitable arms, E, which are inclined upwardly from their lower inner ends and are arranged substantially parallel with the inclined surface of the pan, said arms extending to and above 75 the annular trough or launder, A', which surrounds the periphery of the pan and having their outer extremities connected to appropriate flights or blades, F, which operate in said trough or launder and serve to 80 conduct the sands or dewatered material which are delivered into the trough by the mechanism I will hereinafter describe, along said trough to the discharge openings thereof. Suitable brace rods, G, or the like may 85 be employed to support the outer portion of the arms, if desired.

The arms, E, of which there may be any 90 desired number and which, as before stated, are connected and carried by the vertical revolving shaft, C, have their under surfaces provided with some suitable form of rabbles, 95 blades, or flights, or equivalent means which are designed to engage and successively advance the sands and slimes up the inclined surface of the cone and onto the unsubmerged portion, a, thereof and finally into the annular trough or launder.

While I may use rabbles or flights of any 100 desired construction for effecting the feed of the material over the inclined surface of the conical pan and onto and over an unsubmerged portion thereof of substantial area, I prefer for present purposes, that the flights shall be in the form of curved blades, H, of substantial length and whose middle portions are appropriately secured to the arms. In other words, each of the flights is, preferably, connected about midway of its length to an arm, E, the connection being 105 110

by any well known means, for instance, by bolts or like fastenings, I, which may pass through the arms and through the flanges or lugs, J, on the flights. Whatever connection 5 is used, it should preferably be such that the flights will pivot or be turnable about the fastening to enable said flights to be adjusted to alter their pitch; that is, to render the flights more or less eccentric to the curvature of the pan, which permits me to vary 10 the amount of material which the flights will take and advance up over the inclined surface of the pan to the unsubmerged portion thereof and finally into the annular 15 trough or launder, A', before mentioned.

The flights extend for a considerable distance fore-and-aft of the arms and the length of these flights may be such that the adjacent ends of successive flights may be 20 disposed in overlapping planes; this lap or the distance between the adjacent ends of successive flights may vary according to the different character of the material to be treated.

25 In some cases the adjacent ends of successive flights may not overlap or in fact extend into a common plane which will leave a space, b, as shown in Fig. 5 to permit the material to slide back on the inclined surface of the pan for a slight distance before it is picked up by the succeeding flights.

30 Each of the arms, E, carries a series of the aforesaid flights and the flights of each series vary in length, the shortest flights being operable over the lower portion of the cone and the other flights progressively increasing in length to conform to the increasing diameter of the portions of the pan 35 over which they operate, and the longest flights being disposed near the upper extremity of the inclined surface of said pan and engaging the dewatered material and delivering the same directly into the aforesaid annular trough or launder.

40 In operation, the flights are, preferably, normally set at an angle, and, therefore, it is quite evident that as they are carried around over the inclined surface of the pan, 45 they engage and push aside and progressively crowd the sands and slimes upwardly over the surface of the cone and onto the unsubmerged portion, a, of the same and finally deliver the sands or slimes into the trough or launder, A', along which they 50 are finally carried to the discharge openings, by means of the flights, F, which are fixed to the outer ends of the arms, E, and which operate in said trough or launder.

55 Suitably mounted within the pan and at a suitable distance above the lowest portion thereof, is a feeding device which I have shown for illustrative purposes in the form of an annular feed trough, L, into 60 which the sands and slimes are fed from any

suitable source of supply, said annular feed trough having a series of short pipes, l, on its bottom, and which are designed to act as a feed distributer and which deliver the sands and slimes to the inclined 70 surface of the pan at a point below the water level thereof, the said feed trough being suitably connected to the arms or otherwise arranged so that it may be rotated in unison with the vertical shaft, which carries 75 said arms.

In Fig. 3, I show a modification of the before described apparatus, wherein the ore may be subjected, if desired, to an acid bath, and to this end, the inverted cone, or funnel-shaped pan, A', is stepped between its center and circumference to form a gutter-like portion, M, in which a second series of arms, E', with complementary curved or other rabbles or flights, H', operate, said second 80 arms being inclined substantially parallel with the inclined surface of the pan and which pan, as in Fig. 1, has at its central portion a tubular discharge member, B², substantially as before mentioned in connection with the form of device shown in Figs. 1 and 2.

When using the stepped pan of Fig. 3, each of the inclined portions of the pan will be provided with a suitable feeding device 95 which may be in the form of an annular feed trough, L, L', substantially as described for Fig. 1, said troughs being so connected to the vertical shaft that they are carried by the latter in unison with the arms, which have 100 secured to them the curved flights or conveyors before mentioned, and one of which troughs, say the one, L', which operates in the upper portion of the pan, being supplied with a suitable acid, when the pulp is to be 105 subjected to acid treatment. In this case the sands and slimes are rabbled or conveyed out of the water and upwardly over a submerged inclined surface of the pan and they are discharged into the acid bath in 110 the gutter, M, formed by the stepped portion of the pan and are finally rabbled or conveyed out of the acid bath and upwardly over an unsubmerged portion of the pan and delivered over the periphery thereof 115 into the annular trough or launder before mentioned.

In Fig. 6, an apparatus is shown wherein a series of the aforesaid conical pans, or trays are nested or mounted one above the other, each of the pans having its central overflow communicating one with the other and the several pans deliver their overflow to a suitable point, which arrangement may be used, if desired, and particularly where 125 space is an important consideration.

The apparatus disclosed in Fig. 4 possesses the leading characteristics of those before mentioned, but in this instance the apparatus may also be used as a drier and de- 130

frother on flotation concentrates, or any other concentrates. The apparatus of Fig. 4, includes the inverted cone-shaped pan, A³, and the vertical shaft, C³, with its arms, 5 E³, and curved flights, H³, substantially as before described, said pan having, also, a suitable spray pipe, N, which is designed to act as a defrother; to this end the pipe is positioned adjacent the upper surface of the 10 pulp and in such relation thereto that its spray may act directly upon the froth, said spray pipe being supplied with air, steam, or water admitted thereto through an appropriate pipe, O', which may pass through 15 the central discharge tube of the apparatus, as shown.

The upper portion of the pan of Fig. 4, is also provided with a steam jacket, P, through which steam may be admitted by a 20 pipe, d, and through which steam jacket a suitable return pipe, e, may lead. In this case the radial arms with their rabbles or flights, H³, advance the sands or slimes out 25 of the water and onto and over the part of the inclined surface which is not submerged and finally onto and over the upper inclined 30 surface of the steam jacket, and which latter surface acts as a hot plate or drier for the particles which pass thereover.

35 The general operation of the foregoing types of machine is as follows: The pulp is delivered to the inclined surface of the pan and is distributed by the annular trough in the path of the revolving arms with their 40 curved flights. The solids or heavy material settle on the inclined surface of the pan and are thence conveyed or rabbled up the said surface and onto an unsubmerged part thereof and are finally discharged over the 45 top edge of the pan, and into the annular trough or launder. During this operation the water and some solids overflow the top edge of the central tube which forms an overflow for the fluid matter and also a 50 means for preserving the level of the liquid contents of the pan.

Having thus described my invention what I claim as new and desire to secure by Letters Patent is:

55 1. Apparatus of the character described, having in combination, a stationary pan of substantially funnel-shape in cross section, said pan having a receiving trough for solids surrounding its outer edge and having an overflow for liquid and fine slimes in the center of its bottom; and revolubly mounted members disposed over the inclined surface of the pan having longitudinally curved centrally mounted flights operable therewith over said surface and arranged substantially in spiral form and adapted to progressively move sands and slimes upwardly over said surface, said overflow being sufficiently above the bottom 60 of the pan and below the plane of the top

edge thereof as to leave a drying surface of substantial area over which solids are advanced to said receiving trough, said flights adapted to impart a prolonged particle travel both in the liquid and over the submerged drying portion of the pan. 70

2. Apparatus of the character described having in combination, a stationary pan of substantially funnel-shape in cross section, said pan having a receiving trough for 75 solids surrounding its outer edge and having a tube extending upwardly from the center of its bottom and forming an overflow for liquid and fine slimes and for preserving a fluid level in the pan, said overflow being disposed a sufficient distance below the top edge of the pan to leave a drying surface of substantial area over which the solids are advanced; and members disposed over the inclined surface of the pan 80 having longitudinally curved flights operable over said surface and adapted to progressively move sands and slimes upwardly over said surface and over the unsubmerged drying portion thereof and into said trough, 85 said flights being arranged in substantially spiral form and operating to impart a prolonged travel of the ore particles over both the submerged and unsubmerged portions 90 of the pan. 95

3. Apparatus of the character described having in combination, a stationary pan of substantially funnel-shape in cross section, said pan having a receiving trough for 100 solids surrounding its outer edge and having a tube extending upwardly from the center of its bottom and forming an overflow for liquid, and fine slimes and for preserving a fluid level in the pan, said overflow being disposed a sufficient distance below the top edge of the pan to leave a drying surface of substantial area over which the solids are advanced; and members disposed over the inclined surface of the pan having 105 longitudinally curved flights operable over said surface and adapted to progressively move sands and slimes upwardly over said surface and over the unsubmerged drying portion thereof and into said trough, said flights being arranged in substantially spiral form and operating to impart a prolonged travel of the ore particles over both the submerged and unsubmerged portions 110 of the pan, the adjacent ends of successive flights being arranged in overlapping planes. 115

4. In apparatus of the character described, the combination of a pan having an inclined surface and having a receiving trough for solids at one portion and an overflow and discharge for liquid and fine 120 slimes at an opposite portion, arms disposed over the inclined surface of the pan, longitudinally curved flights extending fore and aft of said arms, said overflow being sufficiently above the bottom of the pan and 125 130

below the plane of the top edge thereof as to leave a drying surface of substantial area at the top over which solids are advanced, and means pivotally connecting the central 5 portions of the flights to said arms whereby the flights may be angularly adjusted relatively to the arms, said flights adapted to impart a prolonged travel to the ore particles both in the liquid and over the unsub-
10 merged portions of said pan.

5. Apparatus of the character described, having in combination, a stationary pan of substantially funnel-shape in cross section, said pan having a receiving trough for 15 solids surrounding its outer edge and having an overflow for liquid and fine slimes in the center of its bottom; and revolutely mounted members disposed over the inclined surface of the pan having longitudinally

curved centrally mounted flights operable 20 therewith over said surface and arranged substantially in spiral form and adapted to progressively move sands and slimes upwardly over said surface, said overflow being sufficiently above the bottom of the 25 pan and below the plane of the top edge thereof as to leave a drying surface of substantial area over which solids are advanced to said receiving trough, said flights adapted to impart a prolonged particle travel 30 both in the liquid and over the submerged drying portion of the pan and an annular feed trough movable with said members and having outlets adapted to deliver material upon the inclined surface of the pan. 35

In testimony whereof I affix my signature.

WALKER J. BOUDWIN.
